UNITED STATES PATENT OFFICE.

GEORGE E. THACKRAY, OF WESTMONT BOROUGH, PENNSYLVANIA.

CONCRETE-COLUMN REINFORCEMENT.

1,413,199.

Specification of Letters Patent. Patented Apr. 18, 1922.

Application filed May 24, 1920. Serial No. 383,624.

To all whom it may concern:

Be it known that I, GEORGE E. THACKRAY, a citizen of the United States, and a resident of the borough of Westmont, county of Cambria, and State of Pennsylvania, have invented certain new and useful Improvements in Concrete-Column Reinforcement; and I do hereby declare the following to be a full, clear, and exact description of the invention, such as will enable others skilled in the art to which it appertains to make and use the same.

My invention relates to reinforcement for concrete, with particular reference to a series of hoops or continuous spiral type of reinforcement used as one of the members in reinforcing concrete columns for buildings, piles, struts and other similar constructions.

My invention generally consists of a rod of steel or other metal wound in the form of a helix, which may be of any desired diameter, forming coils which may be any size and distance apart to suit the design. I may also make my reinforcement of a plurality of hoops, the ends of which may be welded or otherwise joined and arranged substantially parallel and spaced apart as desired.

In order to maintain the coils in proper relation I secure them at two opposite points to a stiffening member or members, which stiffening members may be of steel or other metal formed of a flat, angle, channel, Z bar or any other suitable shape. The stiffening members are provided with holes or perforations at any suitable intervals corresponding to the desired distance apart of the coils, and the coils are secured to the stiffening members by means of wire staples, or by twisted wires. The free ends of the staples are inserted through the perforations of the stiffening members with the loop surrounding the rod of the coil and the free ends are bent or clinched, thus securing the coil in position.

I prefer to arrange these staples or other fastening members to the coils in a slightly loose manner so that the coils while secured in position may be rotated in order that the structure may be collapsed, being almost flat for shipment. This collapsing is accomplished by keeping the stiffening bars parallel and shifting them relatively longitudinally thereby causing the coils to rotate slightly in their fastenings as the stiffening members approach each other.

I generally prefer to use two stiffening

bars, but may use three or more spaced equally apart, but in order to collapse the column reinforcement the stiffening members must be slid together so that they are in adjacent or in opposite positions on the coil proper preparatory to collapsing same. This permits these reinforcements to be readily shipped in railroad cars, wagons, or otherwise, and when received at points of use may be opened to usable forms.

I prefer to secure the coils to the stiffening bars somewhat loosely or in such a manner to permit collapsing or restoration of the structure and also permit the stiffening bars to be slid around the coil for the purpose above described.

Having thus given a general description of my invention, I will now, in order to make the matter more clear, refer to the annexed sheet of drawings, which forms part of this specification, and in which like characters refer to like parts.

Figure 1 is a side elevation of concrete column reinforcement embodying my invention; Figure 2 is a top plan view of the column reinforcement shown in Figure 1; Figures 3 and 4 are detail views illustrating the manner of attaching the helical rod to the reinforcing bars drawn on a large scale; Figure 5 is a top plan view of the bottom clinching die; Figure 6 is a bottom plan view of the top clinching die or tool; Figure 7 is a transverse section through the clinching dies and one of the reinforcing bars at the end of the working stroke, the helical rod and staple being shown in elevation; Figure 8 is a transverse section through one of the reinforcing bars with the helical rod and staple attached thereto shown in elevation; Figure 9 is a longitudinal sectional elevation through one of the reinforcing bars taken at right angles to the portion shown in Figure 8; Figure 10 illustrates an angle stiffener secured to a coil.

Referring now to the characters of reference on the drawings:—1 is the column reinforcement as a whole, 2 are the stiffening bars shown as of channel section although they may be of any other shape desired, 3 are the channel legs or flanges, 4 is the channel web, 5 are holes or perforations in the channel web, 6 is the helical rod preferably made continuous end to end, 7 are the staples for securing the coil to the stiffening members having their ends 8 bent or clinched as shown, 9 is upper die or tool for driving

the staples for purpose of clinching or securing them and the coil and is provided with a recess 10 of curved form adapted to receive the loop end of the staple, 11 is a curved recess in the die or tool 9 adapted to receive and conform to helical rod 6 as illustrated, 12 is the lower clinching die provided with the groove 13 adapted to receive the flanges of the channel and with depressions or notches 14 for receiving the ends of the staples, these notches being curved as illustrated so as to cause bending or clinching of the staples when they are driven or forced into position.

15 Figure 10 shows an angle 17 instead of a channel and 18 is a perforation in the angle to receive the free end of the staple or other securing member.

The manufacture of these reenforcements 20 is accomplished as follows: The rod 6 is coiled on a mandrel or other suitable machine to the diameter required for construction, which may of course be made to suit any size of column and the size of the rod 25 may also be such as to withstand the stress of use. The stiffening members as shown can be made of any length and any number of holes punched therein at any distance apart to suit the desired design. The coiled 30 rod 6 is then superimposed on a bar or long anvil similar to a tinner's stake and provided preferably with a plurality of lower dies 12. Staples are then placed in position 35 in the perforations of the stiffening member over dies 12 with their free ends projecting into the notches 14, and the tool 9 is then pressed or driven downward, causing the staples to assume the position illustrated in Figure 4, thereby bending the ends and 40 clinching them as illustrated and securing the coils in position.

Some of the advantages of my construction are that all the parts are readily procured and can be assembled without expensive tools. This construction has the advantage of securing the stiffening members 45 loosely to the coils, allowing them to be collapsed for easy shipment preparatory to use, thus allowing full car or wagon loads 50 at the lowest rates.

Although I have described and illustrated my invention in considerable detail, I do not wish to be limited to the exact and specific details thereof as shown and described, but may use such modifications in, substitutions for, or equivalents thereof, as are embraced within the scope of my invention, or as pointed out in the claims.

Having thus described my invention, what 60 I claim and desire to secure by Letters Patent is:—

1. A column reenforcement comprising a continuous helical coil, a plurality of stiffening members rotatively and slidably secured 65 thereto by staples, loosely embracing the

coils, passing over the coils, the free ends of which are abruptly bent and clinched against the stiffening members, which members are thus secured to the coils so that the coil and stiffeners may be collapsed when 70 the stiffeners are together or opposite.

2. Column reenforcement comprising a continuous helical coil, a number of stiffening members each provided with a plurality of holes, staples passing over the coils and 75 through said holes and loosely embracing the coils, the free ends of which staples are abruptly bent and clinched against the stiffening members in such a way as to secure said coil slidably and rotatively in 80 position on said stiffening members, whereby the coils and stiffeners may be collapsed when the stiffeners are together or opposite.

3. Column reenforcement comprising a continuous helical coil, two or more stiffening members, perforations in said stiffening members, and staples, loosely embracing the coils, the free ends of which pass through 85 said perforations and are bent at an angle and clinched against the stiffeners in such a 90 manner as to secure the stiffeners slidably and rotatively on the coils, whereby the coils and stiffeners may be collapsed when the stiffeners are together or opposite.

4. Column reenforcement comprising a 95 continuous helical coil, two or more stiffening members, each provided with a plurality of perforations arranged at intervals to correspond to the pitch desired; staples, loosely 100 embracing the coils, the free ends of which pass through said perforations with their loop portions around the rod of said coil, the free ends of the staples being bent and clinched against the stiffening members in such a way as to lightly secure the parts in 105 place, whereby each of the stiffening members is securely though slidably and rotatively mounted on the coil, whereby the coil and stiffeners may be collapsed when the stiffeners are together or opposite. 110

5. Column reenforcement comprising a continuous helical coil, two or more stiffening members, each provided with a plurality of perforations arranged at intervals to correspond to the pitch desired; staples, the 115 free ends of which pass through said perforations with their loop ends around the rod of said coil, the free ends of the staples being bent and clinched against the stiffening members to secure the parts in place, said staples being slightly loose or provided with a very small clearance around said rod to allow relative rotary and sliding movement of the coils and stiffening members, whereby the coil and stiffening members may be 120 collapsed when the stiffeners are together or opposite.

In witness whereof I hereunto affix my signature.

GEORGE E. THACKRAY.
